James Pittig of Waterford, Saratoga County, New York

This schedule is referred to in these Letters Patent and making part
of the same containing a description in the words of the said James
Pilling himself of his improvement in the construction of a cast iron
water-wheel denominated Pilling's horizontal sunk curb-wheel,

Know all men by these presents that I James Bellings, of the village of Waterford, County of Saratoga and State of New York, have invented a new and useful improvement in the construction of a side iron water wheel which I shall distinguish by the name and style of Bellings' Horizontal Side Iron wheel which is constructed as follows:—Upon the bottom end of a perpendicular shaft of suitable dimensions is firmly fixed a cylinder in the form of a shallow inverted cup of cast iron or other materials about three feet more or less in diameter across the barrel or head which is about one foot deep the head or cap of which forms a flange projecting over the outside of the said barrel or head about one foot more or less in proportion to the intended space of the wheel. At the square or corner two angles of which are formed by the projecting flanges on the periphery of said barrel or head are fixed cast iron buckets straight or curved cast iron or so pointed with the outer end extending to within half an inch of the periphery of the said flanges and of the same depth of the barrel or head. In the bottom of the wheel shaft is a female socket receiving a male one which is set firm in the foundation work of a curb which surrounds the bottom and side of the said wheel being circular with a cast iron rim into which the periphery of the said flanges is nicely fitted so as to be as near water tight as possible and not produce friction in its motion. Around the sides of the said curb are several openings the same depth of the wheel and about six or eight inches wide in which extend carriages of the same depth about eighteen inches long through which

which the wheel is to fall) on a long iron bar, usually about 16 feet
of the wheel at intermediate distance between the last nail or
spur given to the bottom of the curb, being given such that water pipes
may be kept from the buckets when the wheel is turned. There is
made a firm recess in the curb to receive the wheel so that when
spur from the pin stick through and into the curb the buckets are
and being counteracted by a spur which is attached to the curb and to the
curb on one side of its center so that the pin stick is suspended
in an upright position calculated to introduce the water in
currents upon the buckets of the wheel when it has turned so that
it may pass the buckets without filling them up so much as to
cause them to sink to the bottom immediately back of the wheel so that
they do not turn, and the balance of the water pipe is an outlet from
the wheel bottom opening. The curb is made of cast iron
spur and bolted or riveted to the rim of the wheel bottom
which is made of steel or other hard iron of the same
wheel or parts. The pin stick gets maybe the ordinary gutter
or right made & turn upon counter bearing by means of a pivot
and perpendicular key shaft. The curb does upon its upper end
and beneath the curb if necessary a strong iron or be given to any of the
water pipe any connection required. The upper end of the wheel
shaft may run in base as usual from which power may be derived
of coupling wheel to hand or otherwise. No portion of this
supposed device is claim'd as my discovery or invention in itself.
The method of introducing the water pipe is to take a pipe from
the wheel by the arrangement as above described & firmly fasten
it to the end of the curb and a hole by which the latter is
brought up to the water pipe is then given to the under side of the
wheel and the bottom of the curb fastened from the pin stick at
an angle of forty five degrees so as to cause of machinery
but not to fall September 11, 1835.
